Parker & Benton
ATTORNEY.

UNITED STATES PATENT OFFICE.

ALBERT EDGERTON THATCHER, OF FENTON, MICHIGAN, ASSIGNOR TO FENTON MACHINE TOOL AND DIE CO., OF FENTON, MICHIGAN, A CORPORATION OF MICHIGAN.

GAS-BURNING STOVE.

Application filed August 27, 1926. Serial No. 131,855.

My invention relates to improvements in gas burners for stoves employing a hydrocarbon fuel.

The object is to provide a stove having a hydrocarbon fuel reservoir and a plurality of gas burners, with improved distributing connections leading from the reservoir to the several burners and adapted to so deliver fuel to the various gas burners as to insure the maximum efficiency of combustion at all times at each burner with the minimum consumption of fuel and wherein the fuel distribution is so equalized that each burner receives its required proportion of fuel to enable it to function in the most highly satisfactory manner.

Other specific objects and advantages will more fully appear from the following specification descriptive of the illustrative embodiment of my invention shown in the accompanying drawing and defined in the appended claims.

In the drawing:

Fig. 1 is a plan of a stove provided with my invention.

Fig. 2 is a perspective of a portion of the gas distributor.

Fig. 3 is a cross-sectional view through the distributor.

Fig. 4 is a perspective of another portion of the distributor.

In stoves of the type to which my invention pertains, a supply of a suitable hydrocarbon fuel is carried within a reservoir indicated herein by the reference character 10. The stove has a plurality of burners 12, four of which are here shown as arranged substantially equidistant from a gas distributor head 14. A fuel pipe 16 leads from the reservoir 10 to the distributor 14. This fuel inlet pipe passes over one of the burners which is provided with a fuel pan, whereby the fuel passing through the inlet is gasified in a manner well known. Valve mechanism terminating in a square stem 18 is provided. This stem 18 is adapted to receive a suitable key whereby it may be actuated to control the supply of fuel.

The burners and reservoir are supported by a frame 20. My invention pertains particularly to the distribution of the fuel to the several burners after it has been gasified and is concerned with the construction of the distributor 14 and its arrangement

with respect to and communication with the several burners 12.

My improved distributor comprises a pair of annular, complementary, threadedly engaged sections 22 and 24. Section 22 has a threaded portion 26 adapted to be received within the threaded portion 28 of section 24. Section 24 is provided with a radially extending tubular inlet 30 adapted to be connected with the conduit 16 which communicates with the reservoir 10. This inlet 30 is cut away as at 32 to provide an atmospheric opening. Side wall portions 33 extend outwardly from this opening.

Section 24 is provided with an interiorly projecting radial wall flange 32 having an axial opening 34. This section 24 constitutes an upper chamber which receives the fuel mixture after the air has mixed with the broken up particles of hydrocarbon fuel. This fuel mixture passes through the axial opening 34 formed in the baffle wall flange 32 into the chamber 22.

Chamber 22 is provided with a plurality of outlets 36 spaced substantially an equal distance apart, one leading to each burner. A conical deflector or baffle 38 extends upwardly axially from the chamber 22 through the opening 34 in the baffle plate 32 into the chamber 24 as shown in Figs. 2 and 3. This conical deflector is positioned axially with respect to the chamber 22 and the outlets leading therefrom.

The outlets 36 are separated from each other by tapered wall portions 40 which extend from the conical deflector to the side wall of the distributor. The gaseous fuel breaks thereover as it enters the outlets 36.

In my improved construction air is mixed with the fuel in the tubular inlet 30 of the distributor. This fuel mixture enters the upper chamber 24 which serves as an intermediate fuel gas mixture storage reservoir and feeds gradually through the restricted opening 34 into the lower chamber 22. The gas mixture is directed by the baffle cone 38 and over the tapered walls 40 into the respective outlets 36 which lead to the burners so that the amount received by the various burners is equalized and the supply is maintained substantially constant in order that the maximum efficiency of each burner will be maintained at all times and under varying conditions.

I claim:

1. In a stove of the character described having a liquid fuel reservoir and a plurality of burners, a fuel gas distributor positioned substantially equidistant from each of the several burners comprising an upper chamber communicating with the reservoir to receive fuel therefrom after the same has been mixed with air and a lower chamber 10 communicating with the upper chamber through a restricted passageway and having a plurality of substantially equidistant fuel outlets, one leading to each burner, and a cone shaped deflector extending upwardly 15 from the lower chamber through said restricted passageway into the upper chamber.

2. In a stove of the character described having a liquid fuel reservoir and a plurality of burners, a gas distributor positioned substantially equidistant from each 20 of the several burners comprising two chambers communicating with each other through a restricted opening, one chamber communicating with the reservoir to receive fuel therefrom after the same has been mixed with air and the other chamber provided with a plurality of substantially equidistant fuel outlets, one leading to each burner, and a cone shaped deflector extending 25 from the one chamber through the restricted opening into the other chamber, said cone shaped deflector positioned axially with respect to said outlets.

3. In a stove of the character described 35 having a liquid fuel reservoir and a plurality of burners, a gas distributor comprising two chambers separated by a baffle plate provided with a restricted axial opening, one of said chambers provided with an inlet leading to the reservoir which inlet has an atmospheric opening, said other chamber provided with an outlet to each burner and a cone shaped deflector projecting through the restricted axial opening 40 in the baffle plate into the first chamber.

4. In a stove of the character described 45 having a liquid fuel reservoir and a plurality of burners communicating therewith, a fuel gas distributor positioned between the reservoir and the burners comprising a pair of complementary threadedly engaged an-

nular sections, one of said sections provided with an interiorly projecting axially apertured radial wall flange positioned in proximity to the other section and an inlet pipe leading to the fuel reservoir which inlet pipe is provided with an atmospheric opening, said other section provided with a plurality of substantially equidistant outlets, one leading to each burner and an axially positioned deflector projecting through the axial aperture in the wall flange of the first mentioned section.

5. In a stove of the character described having a liquid fuel reservoir and a plurality of burners fed therefrom, a fuel distributor between the reservoir and the burners, positioned substantially equidistant from each burner, said distributor comprising upper and lower annular chambers threadedly engaged together, one of said chambers having an inlet leading to the fuel reservoir which passes over one of the burners and is provided with an atmosphere inlet; the other chamber provided with a plurality of substantially equidistant outlets, one leading to each burner, and a baffle plate interposed between said chambers provided with a restricted fuel opening and means arranged with respect to said opening 75 to direct the mixture passing therethrough equally toward the several outlets.

6. In a stove of the character described having a liquid fuel reservoir and a plurality of burners fed therefrom, a gas fuel 85 distributor between the reservoir and the burners, said distributor comprising two chambers, one of said chambers communicating with the fuel reservoir by an inlet pipe that passes over one of the burners 90 and which is provided with an atmospheric inlet; the other chamber provided with a plurality of substantially equidistant outlets, one leading to each burner; a baffle plate interposed between said chambers provided with a restricted fuel opening and a deflector within the distributor axially positioned with respect to said restricted fuel opening and extending therethrough.

In testimony whereof, I sign this specification.

ALBERT EDGERTON THATCHER.
